US00D462760S

(12) **United States Design Patent** (10) Patent No.: **US D462,760 S**
Ahlgrim et al. (45) Date of Patent: **** Sep. 10, 2002**

(54) **MEDICATION DELIVERY APPARATUS**

(75) Inventors: **Dirk Ahlgrim**, Boston, MA (US);
Bradley R. Newman, Avon, IN (US);
Gerd Schmieta, Boston, MA (US);
Dana Lea Schuch, Fishers, IN (US)

(73) Assignee: **Eli Lilly and Company**, Indianapolis,
 IN (US)

(**) Term: **14 Years**

(21) Appl. No.: **29/143,407**

(22) Filed: **Jun. 13, 2001**

(51) LOC (7) Cl. **24-02**

(52) U.S. Cl. **D24/114; D24/112**

(57) **CLAIM**

The ornamental design for a medication delivery apparatus, as shown and described.

DESCRIPTION

FIG. 1 is a front elevational view of the medication delivery apparatus showing our new design;
 FIG. 2 is a rear elevational view of the medication delivery apparatus shown in FIG. 1;
 FIG. 3 is a right side view of the medication delivery apparatus shown in FIG. 1;
 FIG. 4 is a left side view of the medication delivery apparatus shown in FIG. 1;
 FIG. 5 is a bottom view of the medication delivery apparatus shown in FIG. 1; and,
 FIG. 6 is a top view of the medication delivery apparatus shown in FIG. 1.
